UNITED STATES PATENT OFFICE.

JOSEPH C. YOUNGBLOOD, OF ATWOOD, KANSAS.

CARBURETOR CONTROL.

Application filed November 8, 1922. Serial No. 598,821.

To all whom it may concern:

Be it known that I, JOSEPH C. YOUNGBLOOD, a citizen of the United States, residing at Atwood, in the county of Rawlins and State of Kansas, have invented certain new and useful Improvements in Carburetor Controls; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a carburetor control and it is particularly adapted for use in connection with Ford motor vehicles.

The primary object is to provide a simple carburetor control, operable from the instrument board of the vehicle, the mechanism consisting of a minimum number of parts and yet of such construction that it will be inexpensive to manufacture while at the same time being efficient in operation.

25 The novel construction of the invention will be apparent by reference to the following description in connection with the accompanying drawings, in which—

30 Fig. 1 is a detail view of the operating mechanism for the carburetor, the instrument board and dash being shown in section.

Fig. 2 is an enlarged, detail view of the coupling between the manually operated rod and the link connection for the needle valve.

35 Fig. 3 is a detail perspective view of the indicator dial, and

Fig. 4 is a detail view of a connecting loop.

40 Referring now to the drawings by numerals of reference:

1 designates the dash, 2 the cowl and 3 the instrument board of a motor vehicle of known construction. The elements just described represent corresponding elements on the present model of motor vehicle made by the Ford Motor Company of Detroit, Michigan and the invention is shown in connection therewith because it is particularly 45 adapted for use in connection with such a vehicle. Such a vehicle employs a carburetor like that indicated at 4 and it has a needle valve 5 and a choke valve 6. On the stem of the needle valve is a plate 7 having 50 openings 8 and 9 to receive the tines 10 and 11 of the fork 12 which constitutes a link

connection between the manually operated rod 13 and the plate 7. The upper end of the fork 12 is bifurcated with ends 15 and 15' bent over to form a split loop 14. The ends 15 and 15' of the loop engage a stud 16. The lower end of the rod 13' is provided with a split loop 17, projecting through an opening 18 in the stud 16 so that the loop 17 extends through the stud 16 and also through the loop 14. Therefore, there is a universal connection provided between the rod 13 and the forked link 12, the connection being such that a sharp, angular adjustment may be made by a slight turning 70 of the rod 13'.

On the upper end of the rod 13' is a disk 19, the face 20 of which is preferably luminous and the face preferably contains the words "More" and "Less." The purpose 75 of making the disk luminous is to enable the occupant to find it at night and the object of using the words "More" and "Less" is to indicate the direction in which the disk is to be turned for a maximum or a 80 minimum gasoline feed or for adjustments between the two extremes.

Mounted upon the shaft or rod 13' is a stop collar 21 engageable with a stud 22 on the arm 23 of a pivoted elbow lever 24 carried by a bracket 25 on the dash of the vehicle, the stop collar being preferably adjustable on the rod to determine extent of opening of the choke valve and the stud being rotatably mounted on the lever arm to prevent binding of the rod in the stud when the rod is moved longitudinally, as presently described.

The other arm 26 connects to a link 27 which, in turn, connects to the elbow lever 28 of the choke valve 6. The stud and stop 95 22 being loose upon the rod 13' allows the rod 13' to be rotated without affecting the stud.

The rotation of the rod 13' will impart a 100 rotary motion to the fork link 12 so that the needle valve 5 can be adjusted. By pulling up on the rod 13', the stop collar 21 will contact with the stud and guide 22 so that a longitudinal movement can be imparted to 105 it, causing it to swing the arm 26 upward and thereby choke the carburetor.

Attention is called to the fact that with this device a single manually operated rod suffices both for operating the choking mechanism and for operating the needle valve. The elbow lever for the choke valve is set 110

so that it swings over dead center position, which permits the choking to be fully accomplished without raising the choked end of the rod out of the carburetor adjusting head or plate. Thus I can eliminate the necessity of extra rods, brackets, sleeves and sliding joints.

The combination stud and guide on the rod 13' which is connected to the arm of 10 the elbow lever makes a simple means for mechanically connecting the rod 13' to the elbow lever. The combination stud and sleeve serves two purposes: it acts as a bearing for the rod when adjustment is being 15 made and a sleeve for the choking.

The connection between the rod 13' and the elbow lever 25 is very simple and while it is as effective as similar devices now on the market, it is very much easier to manufacture and the universal joint renders the device extremely sensitive in that it can be operated by a minimum turning movement of the rod 13'.

The device is extremely simple to install 25 and will readily perform the function for which it is intended.

What I claim and desire to secure by Letters Patent is:

1. The combination with a motor vehicle 30 of the Ford type comprising a dash having an opening therein, a carburetor having separate choke and needle valves, a bell crank lever mounted on the dash and a link operatively connecting one arm of the bell 35 crank with the choke valve, of a carburetor

control device comprising a rod having operative connection with the needle valve, a second rod extended through the dash opening and connected with the first rod to effect rotary movement thereof, a stud slidable on 40 and rotatably supporting the second rod and having pivotal supporting connection with the other arm of the bell crank and a stop collar on the second rod engageable with the stud to rock the bell crank when the second 45 rod is moved longitudinally.

2. The combination with a motor vehicle of the Ford type comprising a dash having an opening therein, a carburetor having separate choke and needle valves; the latter 50 being equipped with a coupling member, a bell crank lever mounted on the dash and a connecting link between one arm of the bell crank and the choke valve, of a carburetor control device comprising a rod having idle 55 longitudinal and active rotary connection with the coupling member of the needle valve, a second rod extended through the dash opening and having a universal joint connection with the first rod, a stud having 60 a pivotally fixed supporting connection with the other arm of the bell crank lever and having an aperture through which the second rod is slidably and rotatably supported and a stop collar adjustably mounted on the 65 second rod engageable with the stud to rock the bell crank lever when the second rod is moved longitudinally.

In testimony whereof I affix my signature.
JOSEPH C. YOUNGBLOOD.
